UNITED STATES PATENT OFFICE.

SETH W. LOWELL, OF HUME, NEW YORK, AND FRANK A. HOOKER, OF CHARLOTTE, MICHIGAN, ASSIGNORS TO THE STEAM HEAT EVAPORATOR COMPANY, OF CHARLOTTE, MICHIGAN.

APPARATUS FOR BLEACHING FRUIT.

SPECIFICATION forming part of Letters Patent No. 256,341, dated April 11, 1882.

Application filed January 19, 1882. (No model.)

To all whom it may concern:

Be it known that we, SETH W. LOWELL and FRANK A. HOOKER, citizens of the United States, residing respectively at Hume, Allegheny county, New York, and Charlotte, Eaton county, Michigan, have invented certain new and useful Improvements in Fruit-Bleaching Machines, of which the following is a specification, reference being had therein to the accompanying drawings.

Our invention relates to an improvement in fruit-bleaching machines; and it consists in a peculiar construction of parts whereby the sliding frames containing the fruit can be admitted to the apparatus and subjected to the action of the bleaching chemicals without permitting any escape of the vapor during their admission, and similarly withdrawn, as will be more fully set forth hereinafter.

In the accompanying drawings, Figure 1 is a vertical longitudinal section of our invention. Fig. 2 is a vertical cross-section of the same. Figs. 3 and 4 are detailed sections of the sliding doors and fruit-frames. Fig. 5 is a top plan view of the frame.

A represents a suitable rectangular chamber of any desired size, provided with a door, a, on one side, whereby a vessel, a', containing burning sulphur or other chemical compound, may be admitted.

Running lengthwise through the chamber are the grooves or ways B, which extend a suitable distance beyond each end, in which slide the fruit-frames C, consisting of the longitudinal guides c and the connecting cross-bars c', having their outer edges beveled at c². The bottom of the frame is covered with wire-gauze or cloth, as may be desired.

The guides c extend some distance beyond the cross-bars c', and at their ends are beveled away, as shown at c³, Figs. 3 and 5.

Entrance is admitted to the chamber A for the frames C by means of the doors at each end. These doors have a rectangular piece cut from them at their lower corners, as shown at d', Fig. 4, so as to allow the doors to come down and fit closely around the ways B.

The doors D are held in the space between

the two bulk-heads a², and allowed a vertical movement proportionate to the thickness of the fruit-frames, being held down by the spring d, of which there are two to each door. From the under side of the cut-away corners d' of the doors project the pins d², through holes made in the upper sides of the ways, directly in the paths of the beveled portions c³ of the frames, stopping short of the bottom of the grooves, as shown in Figs. 3 and 4.

When sliding the frames into the chamber the beveled portions c³ strike against the pins d² of the doors D, causing the doors to rise against the resistance of the springs d a small way, the bevel c² on the cross-piece c' striking against the under edge of the door and causing it to rise high enough to allow the frames to pass, when the doors close automatically behind them.

The chamber is made of sufficient length to contain any desired number of frames, so that when an additional one is inserted into the chamber it pushes one out through the opposite door, as will be readily understood.

A fruit-bleacher thus constructed is always perfectly tight, none of the fumes from the bleaching compound escaping while inserting and removing the frames. Owing to the projecting ends of the guides c, the frames are always kept sufficiently far apart to allow the vapor to circulate freely around them.

Having thus described our invention, we claim—

1. In a fruit-bleacher, the combination of the doors D, arranged to slide vertically within the ends of the bleacher, with the frames C, the guide-bars of which project beyond the transverse bars c', and have beveled ends c³, substantially as and for the purposes set forth.

2. A fruit-bleacher provided with ways B, the extremities of which project from the ends of the bleacher, with frames C sliding on said ways, and with doors D arranged to slide vertically within the ends of the bleacher, the frames C being provided with guides c', having beveled ends c³, adapted to raise the doors by insertion under their lugs d², and with springs d, adapted to close the doors after the

frames have passed through, substantially as shown and described.

3. A fruit-bleacher provided with ways B, vertically-acting doors D, and frames C, consisting of the guides c and transverse bars c', having their outer edges beveled at c², said guides projecting beyond the bars c', and provided with beveled ends c³, adapted to be inserted under the lugs d² and elevate the doors, to the beveled edges c² adapted to assist the op-

eration by pressing under the bottom edges of the doors, substantially as shown and described.

In testimony whereof we hereby affix our signatures in presence of two witnesses:

SETH W. LOWELL.
FRANK A. HOOKER.

Witnesses:

L. O. SMITH,
RICHARD SMITH.
